UNITED STATES PATENT OFFICE.

LIONEL MANUEL HENDLER, OF BALTIMORE, MARYLAND.

DESIGN FOR AN ADVERTISING DEVICE.

Application filed December 22, 1923. Serial No. 8,123. Term of patent 14 years.

To all whom it may concern:

Be it known that I, LIONEL MANUEL HENDLER, a citizen of the United States, residing at Baltimore, in the State of Maryland, have invented a new, original, and ornamental Design for an Advertising Device, of which the following is a specification, reference being had to the accompanying drawing, forming part hereof.

Fig. 1 of the drawing is a side perspective view of the body;

Fig. 2 is a similar view, taken from the opposite side of the device; and,

Fig. 3 is a similar view, looking from left to right in Fig. 1.

The device comprises a saucer-shaped base, a cone standing upright on the base, and a sphere on top of the cone, with images of animate objects upon the saucer.

What I claim is:

The design for an advertising device as shown and described.

LIONEL MANUEL HENDLER.
